UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

COUPLER-OPERATING-ROD BRACKET

Application filed March 3, 1928. Serial No. 258,786.

This invention relates to coupler operating devices and more particularly to removable means for retaining a revoluble operating rod in its bracket, and has for its object to provide such a removable means which does not require any bolt, nut, cotter or similar retaining means.

Another object is to provide such removable means which is fool-proof in that it cannot be improperly applied.

In the drawings:

Fig. 1 shows a typical application of my device to a railway car.

Figs. 2, 3 and 4 show the relation of the rod with an improved bracket and my retaining device.

The preferred form of the bracket comprises spaced apart walls 2—3, each wall having a slot therein forming a journal 4 for the revoluble operating rod 5 and the projections 6—7 are preferably positioned adjacent the slots and are formed so as not to interfere with the removal or replacement of the operating rod in the bracket.

The helical spring 8 encircles the rod and is of such dimensions that when it is compressed its overall height will permit it to pass between the spaced apart projections and not interfere with the removal or replacement of the operating rod but as soon as the pressure is released on this spring it expands so that its opposite ends engage the spaced apart walls 2—3 of the bracket and a part of the spring 8 is under one or more of the projections 6—7 so that the rod cannot be removed from the bracket by a lateral movement while the spring is in released position.

It will be noted that in my device the operating rod is free to move longitudinally of itself which may be desirable in some types of coupler operating devices.

The accompanying drawings illustrate the preferred form of the invention, thought it is to be understood that the invention is not limited to the exact details of construction shown and described, as it is obvious that various modifications thereof within the scope of the claims will occur to persons skilled in the art.

I claim:

1. The combination of a revoluble car coupler operating rod, a bracket therefor having spaced apart walls, each wall provided with a slot to form a journal for said rod and a projection adjacent each slot, and a helical spring surrounding the rod between said walls and positioned under said projections when free, said elements so proportioned that when the spring is compressed it will clear the projections and permit the lateral removal of the rod.

2. The combination of a car coupler operating rod, a bracket therefor, and means to restrict the lateral movement of the rod comprising a helical spring which when free projects under portions of the bracket but which can be compressed to permit lateral movement of the rod.

3. The combination of a car coupler operating rod, a bracket therefor, and means to restrict the lateral movement of the rod though permitting longitudinal movement thereof comprising a helical spring which when free projects under portions of the bracket but which can be compressed to permit lateral movement of the rod.

ARTHUR E. SMALL.
